UNITED STATES PATENT OFFICE

2,491,163

JUSTIFIER FOR TYPEWRITERS

Earl R. Couden, Chicago, Ill., assignor to Henry Hildebrandt, Chicago, Ill.

Application May 10, 1946, Serial No. 668,958

13 Claims. (Cl. 197—84)

1

This invention relates to justifiers for typewriters for adjustably regulating relative movement between the step by step escapement mechanism and the carriage of the typewriter to make possible the typing of even right hand margins as well as left hand margins.

This invention is directed to improvements over the typewriter justifier shown and described in Szego et al. Patent No. 2,307,339, issued January 5, 1943, wherein the typewriter carriage is separate from the rack bar of the step by step escapement mechanism and the justifier adjustably regulates relative movement therebetween. The justifier includes a support mounted on the carriage, a shuttle plate provided with an inclined slot and reciprocatingly guided on the support and operatively secured to the rack bar of the escapement mechanism, a carrier pivotally mounted on the support and rotated upon movement of the carriage, and an actuator adjustably positioned on the carrier and located in the slot. When the carrier is positioned midway in the slot, no relative motion between the rack bar and the carriage is produced but when the carrier is displaced in one direction or the other, the carriage is relatively positioned in one direction or another with respect to the rack bar as the typewriter is operated and the amount of relative movement depends upon the extent of displacement. In this way more or less letters may be placed in a given typewritten line to form even right hand margins on the typewritten sheet.

However, there are certain disadvantages in the justifier of the Szego et al. patent. The indicating means for indicating the extent of adjustment is not readily discernable, the manner of guiding the shuttle plate is crude and inaccurate, sufficient adjustment is not readily attainable, there is no provision for indicating center or zero adjustment, considerable lost motion and inaccuracies are present between the movable parts which prevents accurate control, it is extremely difficult to obtain even left hand margins, commercial production in quantity is practically impossible, and adaptation to typewriters is difficult.

The principal object of this invention is to provide improvements in a typewriter justifier of this type wherein the above disadvantages are entirely eliminated. In carrying out this object of the invention the support is provided with a guide frame upon which the shuttle plate is reciprocatingly mounted by a sleeve and rod arrangement to provide for true straight line operation and the adjustment indicating means are carried by the guide frame and shuttle plate. The shuttle plate

2

is also provided with a zero or center indicator cooperating with the actuator. A transparent cover is provided to provide for ease of adjustment. The slot in the shuttle plate is elongated to provide a wide range of adjustment. The actuator is adjustably positioned by the screw of the carrier through a set screw which may be adjusted to minimize lost motion therebetween and prevent creeping during the operation of the typewriter. The actuator is provided with a roller working in the slot for ease of operation. The carrier is rotated by a gear segment meshing with a worm gear to obtain proper gear reduction and the gear segment is adjustably mounted on the carrier to prevent binding and minimize lost motion for ease and accuracy of operation.

A back lash spring is provided to eliminate the effects of any lost motion still remaining. The sleeve bearing for the worm gear is held in place by a strap for accurate location thereof. A novel chain and sprocket arrangement is provided for rotating the carrier through the gearing upon movement of the carriage so that the use of bars and the threading of a chain through the typewriter are eliminated. In this latter connection a spring biased drum for the chain is provided and the chain may be of the beaded type. An adjustable cleat for securing the shuttle plate to the rack bar and an adjustable stop for limiting rotation of the carrier are provided for compensating the "bank" of the typewriter and assuring even left hand margins as well as right hand margins on the typewritten page. A reinforced bracket is also provided for attaching the support to the typewriter carriage for eliminating inaccuracies.

Further objects of this invention reside in the details of construction of the various improvements by which the principal object of this invention is attained.

Other objects and advantages will become apparent to those skilled in the art upon reference to the accompanying specification, claims, and drawing, in which—

45 Fig. 1 is a perspective view of the rear of a typewriter with the justifier applied thereto;

Fig. 2 is a perspective view similar to Fig. 1 but showing the justifier in association with the step by step escapement mechanism of the typewriter;

Fig. 3 is an enlarged plan view partly in section of the rack bar and adjustable cleat;

Fig. 4 is a perspective view of the reinforced mounting bracket for the justifier;

Fig. 5 is a top plan view of the justifier;

Fig. 6 is a front elevational view thereof;

Fig. 7 is a perspective view of the worm gear drive for the carrier and also of the clutch;

Fig. 8 is a perspective view of the carrier;

Fig. 9 is a sectional view through the justifier taken substantially along the line 9—9 of Fig. 6;

Fig. 10 is a sectional view of the justifier taken substantially along the line 10—10 of Fig. 6;

Fig. 11 is a perspective view of a portion of the carrier;

Fig. 12 is an exploded view showing the parts of the spring biased drum.

Referring first to Figs. 1 and 2, a typewriter, such as a standard L. C. Smith typewriter, is shown at 10. It includes the usual carriage 11 which is positioned by a step by step escapement mechanism including the escapement means 12 and a rack bar 13. Conventional release bars 14 are secured to the carriage 11 of the typewriter by screws 15 which, in accordance with this invention, extend through slots 16 in the rack bar 13 so that lost motion is provided between the rack bar 13 and the carriage 11.

The rack bar 13 is provided with an extension 17 for operation by the shuttle plate of the justifier 18 which in turn is secured to the typewriter carriage 11 by a reinforced bracket 19. The shuttle plate in the typewriter justifier is operated through the mechanism therein by a pulley or chain sprocket wheel 20 operated by a chain 21. One end of the chain 21 is suitably secured to a stationary portion of the typewriter frame by a screw 22 and the other end of the chain 21 is secured to a spring biased drum 23. The shuttle plate in the typewriter justifier is provided with extensions 24 for operation in conjunction with the rack bar 13.

The justifier 18 provides the connection between the rack bar 13 of the escapement mechanism and the carriage 11 and as the rack bar 13 moves, the justifier causes movement of the carriage 11 and in accordance with the setting of the justifier relative movement between the carriage and the rack bar is adjustably controlled.

Referring now more particularly to Figs. 5, 6, 9 and 10, the justifier 18 includes a support or housing provided with a back wall 27 and side walls 28. The support also is provided with four bosses or posts 29 to which are secured a guide frame 30 by means of screws 31. The guide frame 30 is rectangular in shape and is open in the center. Secured to the guide frame 30 are brackets 32 carrying two pairs of supports 33 for supporting a pair of spaced parallel guide rods 34. The guide rods 34 are held in place in the supports 33 by means of screws 35.

A shuttle plate 37 carries a pair of sleeves 38 which ride along the parallel guide rods 34 so that the shuttle plate 37 is reciprocatingly mounted on the guide frame. The shuttle plate 37 is provided with an elongated, inclined slot 39 which extends beyond the mounting sleeves 38. The shuttle plate 37 is provided with an indicator 40 which is held in place thereon by a screw 41. The indicator 40 cooperates with indicia on a scale plate 42 provided at its ends with slots 43 for the reception of screws 44 for securing the scale plate 42 to the guide frame 30. The slots 43 in the guide plate 42 permit factory adjustment of the scale plate to the proper indicating position. The shuttle plate 37 carries the extensions 24 which cooperate with the extension 17 of the rack bar 13.

A sleeve bearing 47 is secured to the back wall 27 of the support by means of screws 48, and mounted for rotation in the sleeve bearing 47 is

a shaft 49 carrying a carrier 50, the shaft 49 and carrier 50 being held in place in the sleeve bearing 47 by means of a nut 51 and associated washer. The pivotally mounted carrier 50 is provided with a pair of ears 52 for receiving a screw 53. The screw 53 is provided with a shoulder 54 and a nut 55 for preventing longitudinal movement of the screw 53 with respect to the ears 52. The screw 53 is provided with an extension 56 and a knob 57 for rotating the screw. The extension 56 operates within a slot 58 provided in the upper wall 27 of the support or housing.

An actuator in the form of a block 60 encompasses the screw 53 and is guided against rotation by the carrier 52. It is provided with a pin 61 for carrying a roller 62 which operates in the inclined slot 39 in the shuttle plate 37. A set screw 63 extends through the actuator block 60 into the screw thread of the screw 53 so that upon rotation of the screw 53 longitudinal movement is imparted to the actuator 60. By adjusting the set screw 63 the threaded connection between the screw 53 and the actuator block 60 may be adjusted to eliminate lost motion and to provide a sufficient drag to prevent creeping of the actuator block 60 during operation of the typewriter.

Suitably secured to the carrier 50 is a semi-circular plate 65 for carrying a gear segment 66. The gear segment 66 is provided with three slots 67 through which extend screws 68 for adjustably securing the gear segment 66 to the plate 65 and hence to the carrier 50. The purpose of this adjustable connection for the gear segment 66 is to line it up with the operating worm 70 so as to provide minimum lost motion without binding between the parts.

The worm 70 is secured to one end of a shaft and the other end thereof carries a bevel gear 71. A sleeve bearing 72, located between the worm 70 and bevel gear 71 mounts the shaft for rotation and the sleeve bearing 72 is provided with a pair of shoulders 73. The sleeve bearing 72 fits within the cavity 74 in the back wall 27 of the support or housing and is held in place therein by a strap 75 which, in turn, is secured to the support or housing by screws 76. The strap 75 clamps the sleeve bearing 72 in place and it cooperates with the shoulders or flanges 73 on the sleeve bearing for preventing longitudinal shifting thereof. In this way accurate centering and location of the sleeve bearing 72 is provided.

The bevel gear 71 meshes with the bevel gear 77 and is mounted on a shaft 79 carrying a clutch element 80. The shaft 79 is journaled for rotation in the support or housing by a sleeve bearing 81 secured to the housing by screws 82. A complementary clutch element 83 is secured to the sprocket wheel 20, both of which are rotatably mounted on an extension of the shaft 79 so that when the clutch elements 80 and 83 are disengaged, rotation of the sprocket wheel or pulley 20 will not cause rotation of the gear 78 but when the clutch elements 80 and 83 are in engagement, rotation is imparted to the gear 78.

A circumferential channel is provided between the clutch element 83 and the sprocket wheel 20 for receiving the bifurcated end of an arm 84 which is in turn secured by a nut 85 to an actuating rod 86. The rod 86 is journaled in lugs 87 formed on the support or housing and between these lugs the rod 86 carries a spring retainer 88. One end of a coil spring 89 abuts the retainer 88 and the other end abuts one of the lugs 87 so that the spring 89 operates to maintain the clutch elements 80 and 83 in engagement. The rod 86

is provided with a knob or button 90 which, when depressed, operates against the action of the spring 89 to separate the clutch elements 80 and 83. Upon release of the button 90 the spring 89 engages the clutch elements 80 and 83.

The sprocket wheel 20 is preferably provided circumferentially with a plurality of holes 92 connected by the restricted passages 93 for receiving the beaded chain 21. By reason of this particular construction, lost motion between the chain 21 and the sprocket wheel 20 is entirely eliminated so that a positive drive of the sprocket wheel 20 by the beaded chain 21 is provided.

The spring biased drum assembly is illustrated in exploded fashion in Fig. 12 and it includes a base 95 and stud 96, the base 95 being secured to the back wall 27 of the housing or support by means of screws 97. The end of the stud portion 96 is provided with a rectangular slot 98 and a tapped hole 99 for receiving a screw 100. The drum proper includes two parts, 101 and 102, which are held together by the screw 100. The two parts also enclose a spiral spring 103. The outer end of the spring 103 is provided with a slot 104 for engagement on an ear 105 formed inwardly of the member 102 and the inner end of the spring 103 is provided with a slot 106 for engagement with a lug 107 carried by a collar 108. The collar is provided with a rectangular extension 109 which fits into the rectangular slot 98 of the stud 96 and is held against rotation thereby.

When the parts of the spring drum are assembled, the inner end of the spring is held against rotation and the outer end is secured to the drum so that the drum may be wound against the action of the spring to provide tension for the beaded chain 21. The outer flange of the spring drum is provided with a slotted ear 110 for securing one end of the beaded chain 21 thereto.

Adjacent the left hand end of the slot 58 in the upper wall of the housing, there is provided an adjustable stop comprising a clip 111 which is clamped to the housing by a screw 112. The screw 112 extends through a slot 113 in the housing so that the clip 111 may be adjustably positioned. The adjustable stop 111 is provided for the purpose of lining up the screw 53 with the inclined slot 39 when the typewriter carriage is moved to the right hand position in preparation for the typing of a new line.

The carrier 50, as shown in Fig. 11 is provided with an ear 115 for receiving one end of a tension spring 117, the other end of which is connected to a projection 116 formed in the back wall 27 of the support. The tension spring 117 operates to bias all of the movable parts within the justifier in one direction so as to eliminate lost motion and back lash therebetween. In this way the accuracy of the justifier is materially enhanced.

The movable parts within the justifier are encased by a transparent cover 119 which may be made of plastic. The cover 119 has side walls 120 which engage the side walls of the support so as to close the same. However, no side wall is provided at the bottom of the cover as indicated at 121 in Fig. 9, for the purpose of permitting longitudinal movement of the extensions 24 of the shuttle plate 37. The cover 119 is held in place by screws 122 threaded into the guide frame 30. The transparent cover provides ready inspection of the parts encased therein and greatly facilitates the manipulation of the parts and

permits ready visual access to the indicators therein.

The shuttle plate 37 midway between the length of the slot 39 is provided with an indicating mark 123 which cooperates with the roller 62 of the actuator to indicate when the justifier parts are set for the zero or center positions. When the parts are in that position no relative movement is provided between the support and the shuttle plate 37.

One of the side walls 28 of the support is provided with mounting lugs 124 having tapped holes 125 which correspond with holes 126 in the mounting bracket 19 so that the mounting bracket 19 may be readily secured to the justifier support by means of screws. The mounting bracket 19 is provided with a flange 127 which in turn has holes 128 so that the mounting bracket may be mounted on the carriage 11 of the typewriter by the screws which are normally located on the typewriter in those positions. It is necessary that the justifier be rigidly secured to the typewriter carriage to prevent inaccuracies from creeping in and in this respect the mounting bracket 19 is provided with a reinforcing ridge 129 which prevents flexing of the mounting bracket 19 in any direction.

The extensions 24 of the shuttle plate 37 are operatively connected to the extension 17 of the rack bar 13 by an adjustable cleat having two telescoping parts 131 and 132 provided with slots 133 for receiving a screw 134 threaded into a nut 135. By reason of this screw and slot arrangement the spacing between the telescoping elements 131 and 132 may be adjusted to accommodate the extensions 24. The telescoping members 131 and 132 are also provided with slots 136 for receiving screws 137 threaded into the extension 17 so that the position of the adjustable cleat may be longitudinally adjusted on the extension 17. By reason of this construction, lost motion in the connection between the rack bar 13 and the shuttle plate 37 may be eliminated and the exact position of the shuttle plate 37 with respect to the rack bar 13 may be determined. This adjustable cleat connection is extremely important in installing the justifier on the typewriter for it is necessary to compensate for the usual "bank" of the typewriter.

50 This adjustable cleat connection between the rack bar 13 and the shuttle plate 37 and the adjustable stop 111 are so adjusted upon installation of the justifier that the screw 53 is in exact alignment with the inclined slot 39 when the typewriter carriage is moved to the right hand position ready for typing the first letter of a new line and it is by reason of these adjustments initially made that it is possible to obtain a straight left hand margin as well as a straight right hand margin on the typed sheet.

While for purposes of illustration one form of this invention has been disclosed, other forms thereof may become apparent to those skilled in the art upon reference to this disclosure and, therefore, this invention is to be limited only by the scope of the appended claims and prior art.

I claim as my invention:

1. In a justifier for a typewriter for adjustably regulating relative movement between the step by step escapement mechanism and the carriage of the typewriter, the combination of, a support secured to the carriage, a guide frame carried by the support, a shuttle plate provided with 70 an inclined slot and reciprocatingly guided by

the guide frame and operatively secured to the escapement mechanism, a carrier pivotally mounted on the support, means for rotating the carrier upon movement of the carriage, an actuator adjustably positioned on the carrier and located in the slot, indicia on the guide frame, and an indicator on the shuttle plate.

2. In a justifier for a typewriter for adjustably regulating relative movement between the step by step escapement mechanism and the carriage of the typewriter, the combination of, a support secured to the carriage, a guide frame carried by the support, a shuttle plate provided with an inclined slot and reciprocatingly guided by the guide frame and operatively secured to the escapement mechanism, a carrier pivotally mounted on the support, means for rotating the carrier upon movement of the carriage, an actuator adjustably positioned on the carrier and located in the slot, and an indicator on the shuttle plate coacting with the actuator for indicating the center position of the actuator in the slot.

3. In a justifier for a typewriter for adjustably regulating relative movement between the step by step escapement mechanism and the carriage of the typewriter, the combination of, a support secured to the carriage, a guide frame carried by the support, a shuttle plate provided with an inclined slot and reciprocatingly guided by the guide frame and operatively secured to the escapement mechanism, a carrier pivotally mounted on the support, means for rotating the carrier upon movement of the carriage, an actuator adjustably positioned on the carrier and located in the slot, indicia on the guide frame, an indicator on the shuttle plate coacting with the indicia, and an indicator on the shuttle plate coacting with the actuator for indicating the center position of the actuator in the slot.

4. In a justifier for a typewriter for adjustably regulating relative movement between the step by step escapement mechanism and the carriage of the typewriter, the combination of, a support secured to the carriage, a guide frame carried by the support, a shuttle plate provided with an inclined slot and reciprocatingly guided by the guide frame and operatively secured to the escapement mechanism, a carrier pivotally mounted on the support, means for rotating the carrier upon movement of the carriage, an actuator adjustably positioned on the carrier and located in the slot, indicia on the guide frame, an indicator on the shuttle plate coacting with the indicia, an indicator on the shuttle plate coacting with the actuator for indicating the center position of the actuator in the slot, and a transparent cover carried by the support.

5. In a justifier for a typewriter for adjustably regulating relative movement between the step by step escapement mechanism and the carriage of the typewriter, the combination of, a support secured to the carriage, a shuttle plate having guide means for reciprocatingly guiding the shuttle plate on the support and operatively secured to the escapement mechanism and provided with an inclined slot extending beyond the guide means, a carrier pivotally mounted on the support, means for rotating the carrier upon movement of the carriage, and an actuator adjustably positioned on the carrier and located in the slot.

6. In a justifier for a typewriter for adjustably regulating relative movement between the step by step escapement mechanism and the carriage of the typewriter, the combination of, a support

secured to the carriage, a shuttle plate provided with an inclined slot and reciprocatingly guided by the support and operatively secured to the escapement mechanism, a carrier pivotally mounted on the support, means for rotating the carrier upon movement of the carriage, a screw carried by the carrier, an actuator located in the slot and carried by the screw, and a set screw in the actuator engaging in the screw threads of the screw for adjustably positioning the actuator upon rotation of the screw.

7. In a justifier for a typewriter for adjustably regulating relative movement between the step by step escapement mechanism and the carriage of the typewriter, the combination of, a support secured to the carriage, a shuttle plate provided with an inclined slot and reciprocatingly guided by the support and operatively secured to the escapement mechanism, a carrier pivotally mounted on the support, a gear segment adjustably secured to the carrier, means for rotating the gear segment for rotating the carrier upon movement of the carriage, and an actuator adjustably positioned on the carrier and located in the slot.

8. In a justifier for a typewriter for adjustably regulating relative movement between the step by step escapement mechanism and the carriage of the typewriter, the combination of, a support secured to the carriage, a shuttle plate provided with an inclined slot and reciprocatingly guided by the support and operatively secured to the escapement mechanism, a carrier pivotally mounted on the support, a gear segment secured to the carrier, a worm gear for driving the gear segment for rotating the carrier, means for rotating the worm gear upon movement of the carriage, a sleeve bearing for the worm gear, a strap for securing the sleeve bearing to the support, and an actuator adjustably positioned on the carrier and located in the slot.

9. In a justifier for a typewriter for adjustably regulating relative movement between the step by step escapement mechanism and the carriage of the typewriter, the combination of, a support secured to the carriage, a shuttle plate provided with an inclined slot and reciprocatingly guided by the support and operatively secured to the escapement mechanism, a carrier pivotally mounted on the support, an actuator adjustably positioned on the carrier and located in the slot, means for rotating the carrier upon movement of the carriage including a sprocket pulley carried by the support, a spring biased drum carried by the support, and a chain attached at one end to the spring biased drum and coursing the sprocket pulley and attached at the other end to a stationary part of the typewriter.

10. In a justifier for a typewriter for adjustably regulating relative movement between the step by step escapement mechanism and the carriage of the typewriter, the combination of, a support secured to the carriage, a shuttle plate provided with an inclined slot and reciprocatingly guided by the support and operatively secured to the escapement mechanism, a carrier pivotally mounted on the support, means for rotating the carrier upon movement of the carriage, an actuator adjustably positioned on the carrier and located in the slot, and an adjustable stop for limiting rotation of the carrier in one direction with the carrier in alignment with the inclined slot.

11. In a justifier for a typewriter for adjustably regulating relative movement between the step by step escapement mechanism and the car-

riage of the typewriter, the combination of, a support secured to the carriage, a shuttle plate provided with an inclined slot and reciprocatingly guided by the support and operatively secured to the escapement mechanism, a carrier pivotally mounted on the support, means for rotating the carrier upon movement of the carriage, a screw carried by the carrier, an actuator located in the slot and carried by the screw, and an adjustable stop for aligning the slot and screw when the carrier is rotated to one extreme position.

12. In a justifier for a typewriter for adjustably regulating relative movement between the carriage and the rack bar of a step by step escapement mechanism of the typewriter, the combination of, a support secured to the carriage, a shuttle plate provided with an extension and an inclined slot and reciprocatingly guided on the support, an adjustable cleat carried by the rack bar for slidably receiving the extension, a carrier pivotally mounted on the support, means for rotating the carrier upon movement of the carriage, and an actuator adjustably positioned on the carrier and located in the slot.

13. In a justifier for a typewriter for adjustably regulating relative movement between the

carriage and the rack bar of a step by step escapement mechanism of the typewriter, the combination of, a support secured to the carriage, a shuttle plate provided with an extension and an inclined slot and reciprocatingly guided on the support, an adjustable cleat carried by the rack bar for slidably receiving the extension, a carrier pivotally mounted on the support, means for rotating the carrier upon movement of the carriage, an actuator adjustably positioned on the carrier and located in the slot, and an adjustable stop for limiting rotation of the carrier in one direction with the carrier in alignment with the inclined slot.

15 EARL R. COUDEN.
